UNITED STATES PATENT OFFICE.

THOMAS F. KELLY, OF CLINTON, IOWA, ASSIGNOR OF ONE-HALF TO JOSEPH A. KELLY,
OF CLINTON, IOWA.

LOCK FOR CONVERTIBLE FURNITURE.

1,318,287.

Specification of Letters Patent.

Patented Oct. 7, 1919.

Application filed February 4, 1919. Serial No. 274,933.

To all whom it may concern:

Be it known that I, THOMAS F. KELLY, a citizen of the United States, residing at Clinton, in the county of Clinton and State 5 of Iowa, have invented a new and useful Lock for Convertible Furniture, of which the following is a specification.

This invention relates to convertible furniture and more especially to a lock for holding a bed davenport in shut position. While the lock is capable of being used in connection with various kinds of structures and is not necessarily restricted to use in connection with furniture of the type mentioned, it has been designed primarily for use in connection with a bed davenport such as disclosed in Patent Number 1,270,839, issued to W. J. Kelly on July 2nd, 1918.

In a device such as referred to there is provided a housing structure supporting a stationary seat and the sections constituting the bed portion of the device are adapted to fold together and to form the back of the structure when in use as a davenport. In the construction of the bed sections of the device it has been found necessary to use a cross bar as a transverse reinforcement and this bar has necessarily been bent to provide the necessary clearance for the spring fabric 30 of the bed, etc. As a means for locking the folded sections together a latch has heretofore been used for engaging this cross bar. It has been found, however, that in the process of manufacture it rarely happens that 35 two of the cross bars are bent exactly alike, because of variations in the grade of material and other causes. Difficulty has usually been experienced, therefore, in setting the latches on the different structures so as to 40 properly engage the bars. Then, too, the bars sometimes bend out of original shape after shipment and the latches will not properly engage them. It is an object of the present invention to provide a novel form of 45 latch which can be placed in position upon the main or housing structure of the furniture and readily adjusted to properly engage the cross bar of the bed sections, this adjustment being so simple that the services 50 of a skilled mechanic are not required. Another object is to provide a latch which is simple in construction and will not easily get out of order.

With the foregoing and other objects in view which will appear as the description 55 proceeds, the invention consists of certain novel details of construction and combinations of parts which will be hereinafter more fully described and pointed out in the claims, it being understood that various changes 60 may be made in the construction and arrangement of the parts without departing from the spirit or sacrificing any of the advantages of the invention as set forth in the appended claims. 65

In the accompanying drawings the preferred form of the invention has been shown.

In said drawings—

Figure 1 is a side elevation of a bed davenport of the type mentioned, with the 70 near side of the main structure or housing removed and showing the bed sections folded together and fastened in upstanding positions to form the back of the davenport.

Fig. 2 is an enlarged side elevation of the 75 latch in engaging position.

Fig. 3 is a similar view showing the relative positions of the parts during two stages of the locking operation.

Fig. 4 is a front elevation of the latch, the 80 parts being in the positions indicated by dotted lines in Fig. 3.

Fig. 5 is a perspective view of the adjustable segmental plate.

Fig. 6 is a perspective view of the attach- 85 ing bracket.

Referring to the figures by characters of reference, A designates the main structure or housing of the device and secured within this structure is a stationary seat B. The 90 bed portion of the furniture is made up of a back section C, and sections D and E hingedly connected as shown, there being a transversely extending reinforcing bar F carried by said foldable bed portion and so located 95 that, when the bed portion is folded and in upstanding position at the back of the davenport, the said bar will be extended above the sections C, D and E. The bar F is not straight from end to end but has its ends 100 offset as at f and attached to the sides of the bed portion so that when the bed is extended for use, the bar will be supported below and be spaced from the bed fabric. In making these bars, which for lightness, 105 cheapness and durability are tubular, they

are bent in a suitable press but as the quality and strength of the metal varies it is difficult, if not altogether impossible, especially in rapid quantity production, to make the 5 bars without any variation in shape. In practice it has been found that the middle portion of one bar, when fastened to the bed section, will sometimes be as much as one-half or three-quarters of an inch away from 10 the position occupied by the corresponding portion of a similar bar secured to another like bed davenport. This difference may be upwardly, downwardly, backwardly or forwardly from the proper position. In order 15 to provide a latch which, after being placed in position can be adjusted to properly engage the bar F irrespective of any variation in its shape, the device constituting the present invention has been devised. This latch 20 includes an attaching bracket 1 adapted to be secured to the bottom of the top cross rail α of the section A and having a depending ear 2 provided with non-aligning vertical slots 3 and 4, the lower front portion of the 25 ear being cut away as shown at 5. Mounted on one side of the ear 2 is a segmental plate 6 provided at its upper or small end with a laterally extending lug 7 provided with an opening 8, while formed in the plate 6 close 30 to this lug is an opening 9. A pivot stud 10 is seated in the opening 9 and is slidably mounted in the upper slot 3 and heads are provided at both ends of the stud to prevent its removal from the engaged parts and to 35 hold the plate to the ear 2.

An arcuate slot 11 is formed in the broad end portion of the plate 6 and extends across the slot 4. A clamping body 12 is extended through both of these slots 4 and 11 and by 40 tightening the nut 13 thereon, the plate 6 can be clamped tightly against the ear 2 so as to be held against movement relative thereto. By loosening the nut 13, however, the plate 6 can be adjusted angularly about 45 its pivot stud 10 and can also be adjusted longitudinally of the slots 3 and 4.

Extending from the lower front corner of the plate 6 is an ear 14 which is slightly offset laterally and carries a pivot stud 15 50 on which is mounted a curved latch tongue 16 terminating in a blunt head 17. An arm 18 extends backwardly from the pivot portion of the tongue and has a series of openings 19 any one of which is adapted to 55 receive one end of a coiled spring 20 the other end of which is in engagement with the ear 7. This spring pulls upwardly on the arm 18 and holds it normally pressed against a stop finger 21 extended laterally 60 from the lower edge of the plate 6 close to the ear 14. When the arm 18 is thus located the tongue 16 is extended forwardly with the head 17 in the path of the bar F, as shown by dotted lines in Fig. 3. It will be 65 obvious, therefore, that when the folded bed

sections are swung upwardly and backwardly relative to the structure A, the bar F will strike against the head 17 and press it backwardly and upwardly until said bar arrives back of the head 17 whereupon the 70 spring 20 will swing the tongue downwardly so as to straddle and hold the bar. The different positions assumed during this operation have been shown in Figs. 2 and 3. For the purpose of disengaging the latch 75 from the bar F a slide 22 is provided. This slide may be in the form of a stiff wire bent to form an elongated loop one end of which is seated in one of the openings 19 while the other end is bent rearwardly, as at 23 to 80 form a finger piece. This slide is adapted to move within a groove α' formed in the back of the rail α and can be retained therein by any suitable means, such as a screw retained washer 24. By pushing 85 downwardly upon the slide the tongue of the latch will be raised and disengaged from the bar F, as will be apparent.

It will be noted that by mounting the bar engaging member of the latch upon the 90 adjustable plate 6 it is possible, by loosening the bolt 12, to adjust said member to the exact position necessary to cause it to properly engage the bar F, this adjustment being made readily after the bracket 1 has 95 been attached to the rail α and the parts of the bed davenport have been assembled. This allows the structure to be set up at the factory much more rapidly than has been possible heretofore and consequently reduces 100 the cost of the product.

What is claimed is:—

1. A latch including a member mounted for angular and right line adjustment, a clamping bolt for holding the member against movement, an arcuate tongue pivotally mounted on said member, yielding means for holding the tongue normally in one extreme position, and means for shifting the tongue to its other position. 110

2. A latch including an attaching bracket, a plate pivotally and slidably mounted thereon, a clamping bolt extending through the plate and bracket for holding the plate against movement, a latch tongue 115 pivotally mounted on the plate, an arm extending therefrom, a spring connection between the arm and plate, and an actuating member connected to the arm.

3. A latch including an attaching bracket 120 having a slot therein, a plate pivotally and slidably connected to the bracket and having an arcuate slot, a clamping member extending through the slots in the plate and bracket, and a spring controlled latch tongue 125 mounted on the plate.

4. A latch including an attaching bracket having a slot therein, a plate pivotally and slidably connected to the bracket and having an arcuate slot, a clamping member ex- 130

tending through the slots in the plate and bracket for holding the plate against movement relative to the bracket, a stop finger upon the plate, an arcuate latch tongue 5 pivotally mounted on the plate, an arm extending therefrom, a spring connection between the arm and plate for holding the

arm against the finger, and an actuating slide connected to the arm.

In testimony that I claim the foregoing 10 as my own, I have hereto affixed my signature.

THOMAS F. KELLY.
